UNITED STATES PATENT OFFICE.

ROBERT H. BLACKALL, OF PITTSBURGH, PENNSYLVANIA, ASSIGNEE TO RATCHET BRAKE COMPANY, OF NEW YORK, N. Y., A CORPORATION OF DELAWARE.

RATCHET-BRAKE MECHANISM.

1,136,090.

Specification of Letters Patent. Patented Apr. 20, 1915.

Original application filed April 22, 1913, Serial No. 762,943. Divided and this application filed November 10, 1914. Serial No. 871,236.

To all whom it may concern:

Be it known that I, ROBERT H. BLACKALL, a citizen of the United States, residing in Pittsburgh, county of Allegheny, State of Pennsylvania, have invented certain new and useful Improvements in Ratchet-Brake Mechanism, (division of my application Serial No. 762,943, filed April 22, 1913, issued December 8, 1914, as Patent No. 1,120,123;) 5 and I do hereby declare the following to be a full, clear, and exact description of the invention, such as will enable others skilled in the art to which it appertains to make and use the same.

15 My invention relates particularly to hand-actuated brake mechanism of the "ratchet" type, wherein the brake staff is rotated to apply the brakes through the medium of an operating handle, which, when oscillated, 20 imparts a step-by-step rotating movement to the staff.

It is the object of the present invention 25 to provide a brake mechanism of the drop handle type and to provide means independent of the handle for effecting release of the handle from the staff whether the handle is in raised or lowered position. In the embodiment illustrated in the drawings, this 30 release is effected automatically by swinging the handle backward about the staff, and the dropping of the handle is without effect on the clutch members. The construction shown has the further advantage that it permits a graduated or step-by-step release 35 of the brakes.

In the embodiment of the invention illustrated in the drawings, the pivotal support for the handle is carried by a sleeve loosely rotatable upon the brake staff, which sleeve 40 carries a face ratchet for engagement with a relatively fixed face ratchet on the staff, and the automatic unclutching of the handle is effected by causing an inclined bearing face on the ratchet sleeve to engage during 45 reverse rotation of the sleeve with a correspondingly inclined stationary abutment, whereby the relatively movable ratchet member is lifted from engagement with the fixed ratchet member.

50 Another feature of this particular form of unclutching device resides in the provision of stops which by engagement at the end of the unclutching movement serve to prevent further turning movement of the

handle. These may be in the form of lugs 55 at the extremities of the inclined bearing faces.

Although an embodiment of my invention is illustrated in the accompanying drawings, 60 it will be understood that changes in the details of construction may be made within the scope of the claims without departing therefrom.

In the drawings, Figure 1 is a view in side elevation illustrating the handle of my 65 invention applied to a vertically disposed brake staff with the handle in dropped position and the clutch members in engagement; Fig. 2 is a like view but with the handle extended and the clutch members disengaged by the action of the lifting cams; Fig. 3 is a sectional view taken substantially 70 on the plane of line 3-3 of Fig. 1, and Fig. 4 is a fragmentary view illustrating the automatic unclutching mechanism. 75

In the construction shown the brake staff 1 is connected in usual way to the brake rigging of the car, and may be disposed vertically as on passenger coaches and the like. The staff is journaled in suitable bearings secured to the car and is provided with the holding ratchet and pawl ordinarily employed in conjunction with brake applying mechanism. The upper bearing 2 for the 80 brake staff is suitably shaped for attachment to part of a car, as by having lateral extensions 3 for the reception of fastening bolts, and also serves as a housing for parts 85 of the clutch mechanism.

The rotation of the brake staff for the 90 purpose of applying the brakes by hand is accomplished through the medium of clutch mechanism herein disclosed in the form of a face ratchet 4 fast to the staff, and a relatively movable face ratchet 5 95 adapted to convert oscillatory movements of the handle 6, which is carried by the movable clutch member 5, into a step-by-step rotating movement of the staff. The fixed ratchet member 4 is fastened upon the 100 staff as by means of a transverse pin 7, and the movable handle-carrying ratchet member is loosely confined upon the staff so that it may have free rotary movement as well 105 as a movement longitudinal of the staff into and out of engagement with the fixed ratchet member. A transverse pin 8 through the staff at its top prevents complete re-

moval of the upper clutch member. The weight of the movable clutch member will ordinarily insure a positive engagement when the handle is used on a vertical staff.

5 Provision is made for the collapsing or folding of the operating handle in respect to the staff by pivotally connecting the handle with the loose ratchet member or sleeve. The sleeve is for this purpose in 10 the form of the invention herein disclosed provided with a pair of spaced radially disposed pivot lugs 9 which receive between them the inner end of the handle and carry the stud 10 on which the handle is pivotally 15 engaged.

The means for effecting the uncoupling of the handle from the staff automatically in the present disclosure, takes the form of a pair of diametrically opposite lugs or projections 11 integral with the relatively moving sleeve and provided with inclined bearing faces 12, which upon an extreme reverse rotation of the sleeve, ride up the inclined bearing faces 13 on the relatively fixed abutments 14. These relatively fixed abutments 14 may be, as shown, conveniently formed integral with the bearing bracket 2. To limit the reverse movement of the sleeve the coöoperating inclined bearing faces of the 20 lugs and abutments may be provided with extensions 15 and 16 at the upper ends of the inclines, and adapted to engage, as shown in Fig. 4, after the unclutching movement has been effected, to prevent any further rotative movement.

The operation of setting the brakes will be clear from the foregoing description. Upon a forward rotative movement of the handle, the movable clutch sleeve makes 40 positive engagement with the fixed clutch member, and during reverse movement of the handle, the clutch members separate and permit a retractive movement of the movable clutch member. The brake staff may 45 be held during this retractive movement of the handle by means of the usual holding pawl and ratchet not shown. In the case of a vertically disposed brake staff, this pawl may be mounted on the floor or platform of 50 the car in position where the brakeman may control it with his foot in the usual way. The handle is automatically unclutched from the staff simply by continuing the rearward or retractive movement far enough to engage the inclined separating members which 55 act first to lift the movable clutch member, and, when this disengagement is effected, serve to prevent any further rotative movement in that direction.

60 A subordinate feature of improvement embodied in the ratchet brake mechanism herein disclosed, of importance in that it prevents binding between the staff and the upper ratchet element, as that element is 65 lifted to disconnect the handle, is the pro-

70 vision of the duplicate lugs 11 and abutments 14 diametrically disposed on opposite sides of the axis of rotation so that the lift which effects disengagement of the clutch members is symmetrically applied with respect to that axis.

The clutch mechanism is protected, as shown in Fig. 1, by providing the bearing 2 with an integral upstanding annular rim 17, which incloses the fixed clutch member, and 75 by providing a movable sleeve with a dependent annular flange 18, which comes down over and incloses the upstanding rim. The clutch sleeve is also preferably closed at the top by a cap 19 which incloses the end of 80 the brake staff and may be secured in place on the clutch sleeve by a pin 20 driven in through the side of the cap and engaging in alining recesses in the cap and the sleeve. This cap affords a convenient hand-hold 85 whereby the upper clutch sleeve may be lifted by the operator out of engagement with the relatively fixed ratchet when effecting a graduated or step-by-step release of 90 the brakes.

The graduated release is effected by lifting the upper clutch sleeve, and with the operating handle 6 extended, swinging the sleeve forward and then dropping it to get a new grip on the other ratchet. Then the 95 foot pawl on the car platform can be kicked out and the operator can ease off on the brakes by allowing the handle to swing around toward the position at which automatic unclutching is effected, but before 100 there is automatic unclutching, the foot pawl can be again thrown in and the clutch sleeve again lifted and swung forward for another grip on the ratchet, and these operations may be repeated as often as is necessary to effect the desired progressive release of the brakes and without the need for completely releasing the brakes and then partially tightening them up again, as is customary with many types of ratchet brake 110 mechanism having an automatic release.

From the foregoing, it is evident that I obtain all of the advantages of the drop handle type and of graduated or step-by-step release when the invention is used in connection with a vertical brake staff, and that by reason of the fact that the automatic unclutching is effected by means wholly independent of the folding action of the handle, this brake mechanism may be used in places 115 where there would not be room for the folding action of the handle.

I claim:

1. Hand-actuated brake mechanism comprising in combination a brake staff, a face ratchet secured to said brake staff, a second face ratchet positioned to rotate about said staff and gravity actuated to make positive engagement with said first-named ratchet when the brake staff is to be rotated to set 125 130

- the brakes, but sliding thereover on reverse rotation, a handle operatively connected for turning said ratchets to rotate said brake staff forwardly, said handle being capable 5 of folding down close to and substantially parallel with said brake staff while said ratchets remain in operative engagement, means for separating the ratchets when the brakes are to be released forming an upward 10 extension of said second face ratchet and in position to be grasped by the operator for lifting the second ratchet out of engagement while the operating handle is extended, so that graduated release of the brake staff may 15 be effected.
2. Hand-actuated brake mechanism comprising in combination a brake staff, a ratchet clutch member secured to said brake staff, a second clutch member positioned to 20 rotate about said staff and gravity actuated to make positive engagement with said first-named clutch member when the brake staff is to be rotated to set the brakes, but sliding thereover on reverse rotation, a handle operatively connected for turning said clutch members to rotate said brake staff forwardly, said handle being capable of folding down substantially parallel with said brake staff and close thereto, while said clutch members 25 remain in engagement and means at the upper end of said staff and forming an upward extension of said second clutch member, said means being in position to be grasped by the operator for lifting the second clutch member out of engagement while the operating handle is extended so that graduated release 30 of the brake staff may be effected.
3. Hand-actuated brake mechanism comprising in combination a brake staff, a face ratchet secured to said brake staff, a second face ratchet positioned to rotate about said staff and gravity actuated to make positive engagement with said first-named ratchet when the brake staff is to be rotated to set 35 the brakes, but sliding thereover on reverse rotation, a handle operatively connected for turning said ratchets to rotate said brake staff forwardly, said handle being capable of folding down substantially parallel with 40 said brake staff, and a removable cap inclosing the end of the brake staff and secured to an extension of the second ratchet, said cap being in position to be grasped by the operator for lifting the second ratchet out of engagement while the operating handle is extended so that graduated release of the brake staff may be effected.
4. Hand-actuated brake mechanism comprising in combination a brake staff, a face ratchet secured to said brake staff, a second face ratchet positioned to rotate about said staff and gravity actuated to make positive engagement with said first-named ratchet when the brake staff is to be rotated to set 45 the brakes, but sliding thereover on reverse rotation, a handle operatively connected for turning said ratchets to rotate said brake staff forwardly, said handle being capable of folding down substantially parallel with 50 said brake staff and without separating said ratchets, means for automatically separating the face ratchets on substantially complete backward movement of the operating handle, and a removable cap inclosing the end of the brake staff and pinned to an extension 55 of the second ratchet, said cap being in position to be grasped by the operator for lifting the second ratchet out of engagement while the operating handle is extended so that graduated release of the brake staff may be 60 effected.
5. Hand-actuated brake mechanism comprising in combination a brake staff, a stationary bearing member for the staff adapted for attachment to part of a car, a face ratchet secured to said brake staff, a second face ratchet positioned to rotate on said staff and gravity actuated to make positive engagement with said first-named ratchet when the brake staff is to be rotated to set the 65 brakes, but sliding thereover on reverse rotation, a handle operatively connected for turning said ratchets to rotate said brake staff forwardly, said handle being capable of folding down substantially parallel with 70 said brake staff and without separating said ratchets, means for automatically separating the face ratchets on substantially complete backward movement of the operating handle, and a removable cap inclosing the end of the brake staff and pinned to an extension 75 of the second ratchet, said cap being in position to be grasped by the operator for lifting the second ratchet out of engagement while the operating handle is extended so that graduated release of the brake staff may be 80 effected.
6. Hand-actuated brake mechanism comprising in combination a brake staff, a stationary bearing member for the staff adapted for attachment to part of a car, a face ratchet secured to said brake staff, a second face ratchet positioned to rotate on said staff and gravity actuated to make positive engagement with said first-named ratchet when the brake staff is to be rotated to set the 85 brakes, but sliding thereover on reverse rotation, a handle operatively connected for turning said ratchets to rotate said brake staff forwardly, said handle being capable of folding down substantially parallel with 90 said brake staff and without separating said ratchets, means for automatically separating the face ratchets on substantially complete backward movement of the operating handle, and a removable cap inclosing the end of the brake staff and pinned to an extension 95 of the second ratchet and turning therewith, said cap being in position to be grasped by the operator for lifting the second ratchet out of engagement while the operating handle is extended so that graduated release of the 100 brake staff may be effected.
7. Hand-actuated brake mechanism comprising in combination a brake staff, a stationary bearing member for the staff adapted for attachment to part of a car, and lugs integral with said bearing member, said lugs being diametrically disposed with respect to the brake staff and having their front edges inclined to serve as lifting surfaces, a face ratchet pinned to said brake staff, a second face ratchet positioned to rotate about said staff, and gravity actuated to make positive engagement with said first-named ratchet when the brake staff is to be 105 rotated to set the brakes, but sliding thereover on reverse rotation, housing means for said ratchets, a handle operatively connected for turning said ratchets to rotate said 110 brake staff forwardly, said handle being capable of folding down substantially parallel with said brake staff and without separating said ratchets, lugs integral with said second ratchet and having inclined faces adapted to engage with the inclined faces of the lugs on 115 120
8. Hand-actuated brake mechanism comprising in combination a brake staff, a face ratchet secured to said brake staff, a second face ratchet positioned to rotate about said staff and gravity actuated to make positive engagement with said first-named ratchet when the brake staff is to be rotated to set the brakes, but sliding thereover on reverse rotation, a handle operatively connected for turning said ratchets to rotate said 125 brake staff forwardly, said handle being capable of folding down substantially parallel with said brake staff and without separating said ratchets, lugs integral with said second ratchet and having inclined faces adapted to engage with the inclined faces of the lugs on 130

the bearing member and serving to separate the ratchets on substantially complete backward movement of the operating handle, a stop limiting the extent of said backward movement, and a cap inclosing the end of the brake staff and pinned to an extension of the said second ratchet, said cap being in position to be grasped by the operator for lifting the second ratchet out of engagement

10 while the operating handle is extended so that graduated release of the brake staff may be effected.

7. Hand-actuated brake mechanism comprising in combination a brake staff, a stationary bearing member for the staff adapted for attachment to part of a car, a lifting lug integral with said bearing member, a face ratchet secured to said brake staff, a second face ratchet positioned to rotate about said 15 staff and gravity actuated to make positive engagement with said first-named ratchet when the brake staff is to be rotated to set the brakes, but sliding thereover on reverse rotation, housing means for said ratchets, a handle operatively connected for turning said ratchets to rotate said brake staff forwardly, said handle being capable of folding down substantially parallel with said brake staff and close thereto and without separating said ratchets, a lug integral with said 20 second ratchet and adapted to engage with the lug on the bearing member and serving to separate the ratchets on substantially complete backward movement of the operating handle, and a cap inclosing the end of the 25 brake staff and secured to an extension of the said second ratchet, said cap being in position to be grasped by the operator for lifting the second ratchet out of engagement

30 while the operating handle is extended, so that graduated release of the brake staff may be effected.

8. Hand-actuated brake mechanism comprising in combination a brake staff, a stationary bearing member for the staff adapted for attachment to part of a car, said bearing member having an upstanding flange forming a housing, and lugs integral with said bearing member, said lugs being 45 diametrically disposed with respect to the brake staff and having their front edges inclined to serve as lifting surfaces, a face ratchet pinned to said brake staff and inclosed by said housing, a second face ratchet positioned to rotate on said staff and gravity actuated to make positive engagement with said first-named ratchet when the brake staff is to be rotated to set the brakes, but sliding thereover on reverse rotation, housing means for said second ratchet 50 telescopng outside of the housing flange for said first-named ratchet, a handle operatively connected for turning said ratchets to rotate said brake staff forwardly, said handle being capable of folding down substantially parallel with said brake staff, lugs integral with said second ratchet and having inclined faces adapted to engage with the inclined faces of the lugs on the bearing member and serving to separate the ratchets on substantially complete backward movement of the operating handle, a stop limiting the extent of said backward movement, and a cap inclosing the end of the 55 brake staff and secured to an extension of the said second ratchet and turning therewith, said cap being in position to be grasped by the operator for lifting the second ratchet out of engagement while the operating handle is extended, so that graduated release of the brake staff may be effected.

stantially parallel with said brake staff and without separating said ratchets, lugs integral with said second ratchet and having inclined faces adapted to engage with the inclined faces of the lugs on the bearing member and serving to separate the ratchets on substantially complete backward movement of the operating handle, and a cap inclosing the end of the brake staff and secured to an extension of the said second ratchet and turning therewith, said cap being in position to be grasped by the operator for lifting the second ratchet out of engagement while the operating handle is extended, so that graduated release of the brake staff may be effected.

9. Hand-actuated brake mechanism comprising in combination a brake staff, a stationary bearing member for the staff adapted for attachment to part of a car, said bearing member having an upstanding integral flange forming a housing, and lugs integral with said bearing member, said lugs being diametrically disposed with respect to the brake staff and having their front edges inclined to serve as lifting surfaces, a face ratchet pinned to said brake staff and resting on said bearing member and inclosed by said housing, a second face ratchet positioned to rotate on said staff and gravity actuated to make positive engagement with said first-named ratchet when the brake staff is to be rotated to set the brakes, but sliding thereover on reverse rotation, housing means for said second ratchet telescoping outside of the housing flange for said first-named ratchet, a handle operatively connected for turning said ratchets to rotate said brake staff forwardly, said handle being capable of folding down substantially parallel with said brake staff, lugs integral with said second ratchet and having inclined faces adapted to engage with the inclined faces of the lugs on the bearing member and serving to separate the ratchets on substantially complete backward movement of the operating handle, a stop limiting the extent of said backward movement, and a cap inclosing the end of the brake staff and secured to an extension of the said second ratchet and turning therewith, said cap being in position to be grasped by the operator for lifting the second ratchet out of engagement while the operating handle is extended, so that graduated release of the brake staff may be effected.

In testimony whereof I affix my signature, in presence of two witnesses.

ROBERT H. BLACKALL.

Corrections in Letters Patent No. 1,136,090.

It is hereby certified that in Letters Patent No. 1,136,090, granted April 20, 1915, upon the application of Robert H. Blackall, of Pittsburgh, Pennsylvania, for an improvement in "Ratchet-Brake Mechanism," errors appear in the printed specification requiring correction as follows: Page 3, line 9, after the word "released" insert the words *and means*; page 4, line 90, for the word "pined" read *pinned*; and that the said Letters Patent should be read with these corrections therein that the same may conform to the record of the case in the Patent Office.

Signed and sealed this 11th day of May, A. D., 1915.

[SEAL.]

R. F. WHITEHEAD,
Acting Commissioner of Patents.
